UNITED STATES PATENT OFFICE.

JOHN L. OSBORNE, OF ROCHESTER, NEW YORK, ASSIGNOR TO JUDSON GOVERNOR COMPANY, OF ROCHESTER, NEW YORK, A CORPORATION OF NEW YORK.

PUMP-CONTROLLING DEVICE.

1,190,945.

Specification of Letters Patent. Patented July 11, 1916.

Application filed October 26, 1915. Serial No. 58,022.

To all whom it may concern:

Be it known that I, JOHN L. OSBORNE, a citizen of the United States, and resident of Rochester, in the county of Monroe and State of New York, have invented certain new and useful Improvements in Pump-Controlling Devices, of which the following is a specification.

This invention relates to controlling devices for pumps, and is particularly applicable to pumps of the kind commonly known as air-compressors, although it includes novel features applicable to vacuum-pumps or to pumps of other kinds.

In devices for controlling the operation of pumping-engines it is common to employ speed-controlled means, usually of the well-known centrifugal type, and also means controlled by the pressure of the pumped fluid, these two means being arranged to operate, either conjointly or independently, upon a governor-valve, so as to control the admission of motive fluid to the engine with regard both to limitation of its maximum speed, and to an automatic reduction of the speed when the pressure of the pumped fluid approaches the predetermined point. It is also common to combine, with the parts above described, automatic means for unloading or relieving the pump, either by holding its inlet-valves open or in various other ways, upon the attainment of the predetermined pressure.

One object of the present invention is to coordinate in one system, the several means above referred to in such a manner as to secure a uniform and reliable regulation of the engine controlled by the governor, particularly with respect to the various speeds at which the engine is designed to operate under the various conditions of use. To this end I employ, in addition to the usual pressure-controlled means for controlling the engine-speed when the pressure is near but not at the predetermined amount, an auxiliary pressure-controlled means, operable independently of the main pressure-controlled means and of the speed-controlled means, to cause a final movement of the governor-valve to its closed position coincidently with the operation of unloading the pump.

Another object of the invention is to provide, in the fullest possible manner, for ad-

justment of the several elements of the device in such a manner that the speed of operation of the engine under the various conditions encountered may be predetermined with accuracy, and to this end I provide the adjusting-means associated with the several elements of the device in the manner hereinafter described.

Other objects of the invention, and the features of construction by which the several objects are attained, will be set forth hereinafter in connection with the description of the illustrated embodiment of the invention.

In the accompanying drawings:—Figure 1 is a side-elevation of the principal parts of a device, with the exception of the unloader, embodying the present invention, with the centrifugal mechanism shown in vertical, axial section; Fig. 2 is a horizontal section on the line 2—2 in Fig. 1; Fig. 3 is a partial front-elevation of the centrifugal mechanism; Fig. 4 is a partial front-elevation, partly in section, showing particularly the main pressure-controlled element of the device; Fig. 5 is a side-elevation, partly in vertical section, showing the two pressure-controlled elements and the parts immediately associated with them; and Fig. 6 is a side-elevation, partly diagrammatic in character, showing a modified arrangement of the pressure-controlled elements of the device and the parts associated therewith.

The invention is illustrated as embodied in a controlling device adapted particularly to be used in an air-compressor, this device comprising a centrifugal speed-controlled element, main and auxiliary pressure-controlled elements, mechanism for connecting the elements just recited with a throttle-valve or governor-valve, an unloader, and a pilot-valve connected with the unloader and the auxiliary pressure-controlled element and adapted to control their operation conjointly.

The centrifugal mechanism of the illustrated device is shown particularly in Figs. 1 and 3. It comprises two weights 10, which are rotated in a vertical plane by a connection with a horizontal drive-shaft 11 journaled in a stationary sleeve 12. The shaft carries, at its rear end, a pulley 13 by which it may be belted to the engine which is to be governed. A sleeve 14, fixed to the

forward end of the shaft 11, is provided with two radial guideways each comprising two parallel arms 15 between which the weights 10 are embraced. Each weight is provided with a pair of guide-rollers 16 which engage and move in slots 17 in the inner surfaces of the arms 15, the arrangement being such that the weight may move freely in a radial direction and may also have a limited angular movement, while being restrained against lateral or fore-and-aft movement with respect to the guideway. The inner end of each weight 10 is bifurcated, and provided with a pivot-pin 18 by which it is connected with one arm 19 of a bell-crank lever. The levers are mounted on pivots 20 in brackets 21 projecting integrally from the sleeve 14, and the shorter arm 22 of each bell-crank lever has the form of a gear-segment, the two segments meshing together so that the movements of the levers and of the weights shall be always simultaneous and equal.

The centrifugal tendency of the weights is resisted by a centripetal spring 23, which is arranged coaxially with the shaft 11 and is partly embraced within a recess therein. The forward end of the spring rests against a ball-race 24 constituting one part of a ball-bearing, the other race 25 being engaged by lugs 26 integral with the arms 22. When the weights 10 move outwardly they swing the bell-crank levers in a direction to press the spring 23 rearwardly against the ball-bearing, and thus compress the spring 23, while the bearing permits this pressure to be transmitted without substantial friction, while the spring remains fixed against rotation.

The rotating parts just described are all inclosed within an oil-tight casing 27, of which the rear portion is integral with the sleeve 12, as shown in Fig. 1, this casing being thus stationary. The inner end of the spring 23 rests against a collar 28 fixed on a rod 29, which projects forwardly through the front of the casing and is screw-threaded for engagement with an adjusting-nut 30. A key and keyway connect the rod 29, against rotation, with the casing, so that rotation of the nut 30 causes a longitudinal movement of the rod, thus varying the degree of compression of the spring 23 for any given position of the weights 10. In this manner the strength of the centripetal spring 23 may be varied at any time to change the normal speed of the centrifugal mechanism.

While the construction of the centrifugal mechanism as illustrated and just described involves various novel features, these features are not claimed herein, as they are disclosed and claimed in an application for Letters Patent of the United States filed of even date herewith, and it will be under-

stood that, in so far as the present invention is concerned, the particular form of centrifugal mechanism employed is immaterial.

In Letters Patent of the United States No. 963,803, granted to me July 12, 1910, I have disclosed a combined governor and regulator for air-compressors in which the centrifugal mechanism is arranged to rotate about a horizontal axis and is combined with safety-stop mechanism of a peculiar form, and with a governor-valve of a rotary form. In the present apparatus the same general arrangement is employed, and it may be understood that the mechanism, in so far as it is not particularly illustrated and described, may be the same as that of my said patent. Accordingly, the action of the centrifugal mechanism is transmitted to the governor-valve through the intermedium of a sleeve 35 which embraces and slides longitudinally upon the sleeve 12 in which the shaft 11 is journaled. A collar 31 is arranged to slide loosely upon the exterior of the sleeve 14, and this collar 31 has integral extensions 32 which bear against the rear surface of the ball-race 25. The rear extremity of the collar 31 engages a collar 33 which also slides on the sleeve 14, and this latter collar is provided with studs 34 which slide loosely through openings in the rear wall of the casing 27 and which abut loosely against the forward end of the sleeve 35. As in my said patent, the bearing-sleeve 12 is supported by studs 36 mounted in a fork 37 which is swiveled upon the upper end of a column 38, this column rising from the top of the casing 39 in which the rotary governor-valve (not shown) is inclosed. The valve is provided with a stem 40 by which it may be rotated, the upper end of the stem being fixed to a short shaft 41 which turns in a bearing 42 projecting from the column 38, all as in my said patent.

Fixed to the upper end of the shaft 41 is a lever having an arm 43 upon which is mounted a roller 44. This roller is in position to be engaged by a lug 45 which projects from the lower surface of the sleeve 35. The longitudinal movement of the sleeve produced by its connection with the centrifugal mechanism, as above described, causes the lug to engage the roller and move it rearwardly, thus swinging the arm 43 and rocking the shaft 41 and the stem 40 in a direction to move the governor-valve toward a closed position. Since the connection between the centrifugal mechanism and the shaft 41 is merely force-closed, however, the shaft is always free to be rotated by other means, in the same valve-closing direction, beyond the range of influence of the centrifugal mechanism.

The opening movement of the governor-valve is produced by means of a spring 47, which is inclosed within a sleeve 46 integral

with the arm 43. This spring surrounds and acts against a stem 48 which slides through the sleeve, the pointed end of the stem being seated in a socket in a lug 50 projecting from the bar 42. The spring 47 is preferably made of only such strength as is necessary to overcome the frictional resistance of the valve and its stem to rotation, so that the valve is opened by it only when there is no tendency on the part of the centrifugal mechanism or other elements of the governor to close the valve.

In Letters Patent No. 1,136,607, granted to me April 20, 1915, I have disclosed a governor for compressors which operates on the same general principle as the governor of my Patent No. 963,808, but in which the pressure-controlled mechanism contains various improvements. The present invention is illustrated as provided with a pressure-controlled element, resembling, in its general construction and arrangement, that disclosed in my Patent No. 1,136,607. As in said patent, a cylinder 51 fixed to the frame 25 of the governor is connected, by a pipe 52, with the compressed-air receiver supplied by the compressor, and the receiver-pressure is thus effective against a piston 53 which slides loosely in the lower part of the cylinder. Upon a pivot-stud 54, at one side 30 of the cylinder, is mounted a bell-crank lever, having a horizontal arm 55 which engages the top of the piston, and a vertical arm 56 which co-operates with a lever 57 which turns upon a pivot-stud 58 at its upper end. The studs 54 and 58 are mounted 35 in a hollow bracket 60 integral with the side of the cylinder.

The lower end of the lever 57 engages the end of an arm 61 integral with the arm 43. When the piston 53 rises it rocks the levers in a direction to swing the arm 61 in a clockwise direction, so as to move the governor-valve toward closed position, against the slight opposition of the spring 47, the roller 44 at this time moving freely away from the lug 45 so that the valve may be acted upon by the pressure-controlled element, while the governor is entirely independent of the action of the centrifugal mechanism.

As in my said Patent No. 1,136,607, the rising movement of the piston 53 is opposed by a counter-pressure spring. To this end the piston is provided with bifurcated upward extensions 62 which engage a disk 63, which is engaged, in turn, by the lower end of a plunger 64. The counter-pressure spring 65 surrounds this plunger, and its force is adjustable by means of a sleeve 66 threaded into the upper end of the cylinder 51. In Fig. 5 the plunger and the disk 63 are shown in their lowermost position, with the piston raised into engagement with the disk, but not subjected to sufficient pressure 60 to raise the disk from its seat. In this posi-

tion of the parts the lever 57 has no influence upon the arm 61, and it is out of engagement therewith except when the governor-valve is in its extreme open position corresponding with the innermost position of the governor-weights, as shown in the drawings.

As the pressure of the pumped fluid in the receiver rises the piston 53 is forced upwardly with increasing force, until it begins to overcome the pressure of the spring 65, 75 whereupon the piston rises from the position of Fig. 5, compressing the spring and rocking the levers so as to swing the arm 61 and move the governor-valve toward closed position, as above described. This action is 80 gradual, owing to the slight increase in the force of the counter-pressure-spring as it is compressed, so that the governor-valve is gradually closed, and the speed of the pumping-engine decreases until a minimum 85 speed is attained, when the piston 53 has reached its uppermost position. In order that this position, and this minimum speed of the pump when running loaded, may be adjusted, I employ a stop-screw 67 which 90 is threaded into the cylinder-wall in position so that its lower end may be engaged by the top of the piston 53, as shown in Fig. 4. When the piston engages this stop it can no longer move upwardly, and therefore any 95 further slight increase in the receiver-pressure will not result in a further closure of the governor-valve through the action of the piston 53.

It will be noted that in the above described arrangement either the centrifugal mechanism or the main pressure-controlled element of the governor may move the governor-valve toward closed position independently, according to the various conditions 100 encountered in the operation of the pump, so that there is no conjoint action of these elements, nor any substantial automatic change in the normal speed of the governor. This general mode of operation is not 105 claimed herein as novel, since it is identical with that disclosed in United States Letters Patent to J. Willis Gardner No. 638,412; but I claim as novel certain specific features 110 of the form and arrangement of the mechanism by which that mode of operation is 115 adapted for use in a governor of the present design.

In my Patent No. 1,136,607 I disclose an arrangement in which the piston of the 120 pneumatic element of the compressor-governor acted, upon the attainment of the predetermined maximum pressure in the receiver, both to open an unloader-controlling valve, and to simultaneously move the governor-valve to a more nearly closed position.

In the present construction I relieve the piston of the main pressure-controlled element entirely of the performance of these functions, and instead I employ an arrange- 130

ment in which a second or auxiliary element or motor is provided, for the purpose of moving the governor-valve toward closed position coincidently with the operation of an unloader. In the preferred form of the invention this auxiliary pressure-controlled element is not subject directly to the receiver-pressure at all times, but an automatic relief-valve or pilot-valve is employed to introduce compressed air or pumped fluid simultaneously to the auxiliary pressure-controlled member and the unloader, upon the attainment of the predetermined pressure.

The auxiliary pressure-controlled member comprises a cylinder 68 which is shown, in Figs. 1 to 5 inclusive, as located alongside the cylinder 51. Within the cylinder 68 a piston 69 slides vertically, and the lever-arm 55 is extended through an opening in the side of the cylinder 51, so that its end 70 lies above the upper end of the piston 69. The admission of compressed air to the cylinder 68 is controlled by an automatic pilot-valve 71, which communicates with the lower part of the cylinder 51 through a nipple 72, and which is adapted, when the predetermined pressure is attained, to discharge air through a port 73 into the cylinder 68. I have not illustrated or described the construction of the pilot-valve, as such devices are well known, and in the present case the valve may be similar, for example, to that disclosed in U. S. Letters Patent No. 1,141,975, granted to me June 8, 1915. At the same time that the pilot-valve admits air to the cylinder 68 it also discharges air through a pipe 173, which may be connected with a relief-device or unloader of any ordinary or suitable form on the compressor. The result of this operation of the pilot-valve is to simultaneously unload the compressor and move the governor-valve toward closed position, this latter operation being performed by the action of the piston 69 on the lever 55 and the other parts connecting this lever with the governor-valve. This movement of the valve occurs independently of both the centrifugal mechanism and the main pressure-controlled element of the governor, since the lever-arm 55 is free to move away from engagement with the piston 53, which has been arrested in its uppermost position by the stop-screw 67, while the roller 44 on the arm 43 is equally free to move away from the stop 45, and will have done so, in fact, previous to the operation of the auxiliary pressure-controlled element.

It is desirable that the position of the governor-valve, when the pump is running unloaded, be adjustable in order to adjust the minimum speed of the compressor at this time. For this purpose I employ a stop-screw 74 threaded into the bracket 60 in posi-

tion to engage a shoulder 75 on the lever 57, 65 as shown particularly in Fig. 5. In this manner the movement of the lever 57, under the influence of the piston 69, is limited, and since this movement occurs entirely beyond the range of movement imparted to the lever 57 by the piston 53, the action of the stop 74 is determined entirely independently of the action of the stop-screw 67.

While I have shown and above described the auxiliary pressure-controlled element as arranged to act upon the same lever-arm as the piston 53, and the pilot-valve as immediately associated with the elements of the governor and arranged to receive compressed fluid from the cylinder 51, this arrangement is not essential to the mode of operation of the device, but is adopted only for convenience in construction. An alternative arrangement is shown in Fig. 6. In this arrangement the receiver 78, the pilot-valve 79 and the unloader 83 are shown diagrammatically. The pilot-valve is located at any convenient point and is connected directly with the receiver by a pipe 80. The discharge from the pilot-valve flows through branch-pipes 81 and 82, the first of these pipes being connected with the cylinder 76 of the auxiliary pressure-controlled element, and in this case this cylinder is fixed in horizontal position to the side of the cylinder 51, 95 so that the piston 77 may co-operate directly with the arm 61, this arm being extended in length sufficiently for the purpose. The unloader 83 is shown as of a well known type adapted to hold open the inlet-valves of the compressor, such an arrangement being shown, for example, in the patent to Hill, No. 844,801.

The adjustable stop, to determine the position of the governor-valve when the compressor is running unloaded, may be associated directly with the auxiliary pressure-controlled element, as shown in Fig. 6. For this purpose the piston 77 is provided with a lug 84, and the cylinder 76 with a lug 85. A stop-screw 86, threaded into the lug 85, passes loosely through a perforation in the lug 84, and is provided with a head 87 which engages and arrests the lug 84 in a position determined by the adjustment of the screw. 115

The arrangement in which the pilot-valve or pressure-controlled member acts simultaneously to throw into operation an unloader, and to move the governor-valve toward closed position, is not claimed as broadly 120 novel herein, since it is disclosed in U. S. patent, to George R. Cullingworth, No. 827,104, but it is novel, so far as I am aware, to combine this arrangement with a governor having also a pressure-controlled element for 125 operating the governor-valve, this second or main pressure-controlled element being arranged to act upon the valve at a lower pres-

sure than that to which the auxiliary pressure-controlled element is responsive.

The operation of the controlling device as a whole is as follows: When the pressure in the receiver is low the pistons 53 and 69 are in their lowermost positions, and the governor-valve is solely under the influence of the centrifugal mechanism, which is set to operate the pump-engine at a high speed so as 5 to build up the receiver-pressure quickly. At this time the lug 45 is in engagement with the roller 44, thus acting to close the governor-valve whenever the engine tends to attain an unduly high speed. When the 10 predetermined receiver-pressure is attained the piston 53 rises, and thus, through the arm 61, acts to move the governor-valve toward closed position, out of the range of influence of the centrifugal mechanism, so 15 that the speed of the engine is thereby reduced and is thereafter under the control of the main pressure-controlled element alone. In this manner, as the pressure continues to rise, the valve is gradually closed 20 until the engine has attained the minimum speed determined by the stop-screw 67. If the consumption of the compressed fluid is not sufficient to utilize that which the pump is now supplying the pressure continues to 25 rise, and upon the attainment of the predetermined maximum the pilot-valve admits compressed air to the auxiliary pressure-controlled element and to the unloader simultaneously, whereupon the pump is unloaded 30 and at the same time the governor-valve is turned to its ultimate position, as determined by the stop-screw 74, thus allowing the pump to run unloaded at the speed determined by the adjustment of the stop. 35 When the pressure falls again the above-described operations take place in their reverse order.

My invention is not limited to the embodiment thereof hereinbefore described and 40 illustrated in the accompanying drawings, but may be embodied in various other forms within the nature of the invention as it is defined in the following claims.

I claim:

- 50 1. A pump-controlling device having, in combination, a valve-actuating member; a pressure-controlled element coöperating with said member and arranged to move it in a direction to close the valve as the pressure rises; and a second pressure-controlled element also coöperating with said member and adapted to move it toward closed position, independently of the first pressure-controlled element, upon the attainment of a predetermined maximum pressure.
- 55 2. A pump-controlling device having, in combination, a valve-actuating member; two pressure-controlled elements independently operable upon said member to move it in a

direction to close the valve; and means for 65 adjusting, independently of each other, the effective ranges of action of the respective pressure-controlled elements.

3. A pump-controlling device having, in combination, a valve-actuating member; two 70 pressure-controlled elements independently operable upon said member to move it in a direction to close the valve; and means for adjusting, independently of each other, the pressures to which the respective pressure- 75 controlled elements are responsive.

4. A pump-controlling device having, in combination, a valve-actuating mechanism; two pressure-controlled elements operable independently upon said mechanism to move 80 it in a direction to close the valve; adjustable means for limiting said movement of the valve-actuating mechanism; and adjustable means for limiting the movement of one of the pressure-controlled elements. 85

5. A pump-controlling device having, in combination, a valve-actuating member; a pressure-controlled element operable upon said member to move it in a direction to close the valve; a second pressure-controlled 90 element operable in the same manner on the valve-actuating member; an unloader; and a pivot-valve controlling simultaneously the admission of pressure to the second pressure-controlled element and the unloader. 95

6. A pump-controlling device having, in combination, a pressure-controlled element adapted to move a governor-valve toward closed position in consequence of a rise in pressure of the pumped fluid; and means, 100 independent of said pressure-controlled element, for simultaneously unloading the pump and moving the valve farther toward closed position upon the attainment of a predetermined pressure in the pumped fluid. 105

7. A pump-controlling device having, in combination, a valve-actuating member; speed-controlled means, a main pressure-controlled element and an auxiliary pressure-controlled element, all operable independently on said member to move it in the same direction; and an unloader operable conjointly with the auxiliary pressure-controlled element. 110

8. A pump-controlling device having, in combination, a valve-actuating member; speed-controlled means operable on said member; a pressure-controlled element also operable on said member; an unloader; and a pilot-valve connected with said pressure-controlled element and the unloader and adapted to throw them simultaneously into operation upon the attainment of a predetermined pressure in the pumped fluid. 120

9. A pump-controlling device having, in combination, a rotary valve, provided with a spring adapted to open the valve, and a valve-actuating member by means of which

it may be closed against the action of the spring; centrifugal mechanism adapted to act upon said valve-actuating member to move the valve toward closed position, in 5 opposition to the spring; and pressure-actuated mechanism adapted to act upon said valve-actuating member, independently of the action of the centrifugal mechanism, to close the valve in opposition to the spring.
10 10. A pump-controlling device having, in combination, a rotary valve, provided with a spring adapted to open the valve and arms

whereby it may be closed against the action of the spring; centrifugal mechanism; a sleeve having connection with the centrifugal mechanism whereby it is caused to move longitudinally to engage one of said arms and move the valve toward closed position; and pressure-actuated mechanism adapted to act upon said other arm, independently of the action of the centrifugal mechanism, to close the valve in opposition to the spring. 15 20

JOHN L. OSBORNE.
